UNITED STATES PATENT OFFICE

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed December 31, 1926. Serial No. 158,294.

This invention relates to improvements in kerf cutting mining machines and more particularly to machines of the type mounted permanently upon a wheeled support.

5 The principal object of the present invention is to provide a machine of the class described in which a pivotally movable cutter bar may be carried in various positions to cut kerfs in planes varying from the horizontal 10 to the vertical.

The invention may be best understood by reference to the accompanying drawings which illustrate one embodiment of my invention.

15 In these drawings:

Figure 1 is a side view of a machine constructed in accordance with my invention, with parts broken away and shown in longitudinal cross-section;

20 Figure 2 is a plan view of the machine shown in Figure 1;

Figure 3 is a view similar to Figure 2 but drawn to a smaller scale and showing the cutter arm in certain permissible positions there- 25 of; and

Figure 4 is a front view of the machine shown in Figure 1 illustrating the manner in which the machine may be adjusted to cut the kerf either in a horizontal or in a vertical 30 plane.

Referring now to details of the drawings, the machine includes a base frame 1 mounted on axles 2, 2, having supporting wheels 3, 3. A turntable 5 provided with a central bearing 6 is mounted for rotatable movement on said base frame and is provided with a plurality of upright standards 4, 4, thereon. As herein shown these standards are mounted in pairs spaced on opposite sides of the turntable 35 between which is supported a sub-frame 7 carrying the cutting element of the machine. As shown herein, the sub-frame is vertically adjustable with respect to the uprights 4, 4. This adjustment is provided by means of a 40 plurality of pinions 8, 8, carried on shafts 56, 56, extending through upright arms 9, 9, of sub-frame 7 and engaging racks 10, 10, on the upright supports 4, 4. Actuating mechanism for said pinions will be hereinafter 45 described.

The cutting element comprises a cutter arm 15 projecting forwardly of the machine and when in use being provided with a cutter chain 15^a which may be of the usual construction. The cutter arm is rigidly mounted on the forward end of a supporting plate 16 which is pivotally movable about an axis adjacent its rear end on the top of a swinging frame 18. Said supporting plate is mounted about a ring 28^a formed integral with an upwardly projecting sleeve 28 which extends through and has thrust support on the upper end of a main supporting bearing 29 formed integral with the swinging frame 18.

The swinging frame is provided with a pair 65 of stud projections 20^a and 21^a at the front and rear ends thereof, having bearing support in journals 20 and 21 formed in the upper end of respective arms 7^a, 7^a, of the sub-frame 7. This arrangement of bearings, (as illustrated 70 in Figure 1) is such as affords a trunnion support at front and rear end of said swinging frame wherein the complete cutting mechanism including the cutter arm, and the swinging frame with all driving mechanism may 75 be bodily rotated about the axis extending longitudinally of the machine.

A motor 25 is mounted on the swinging frame 18 preferably near the forward end thereof as shown, and has a driving pinion 80 26 engaging the bevel gear 27 keyed adjacent the lower end of the sleeve 28 which is rotatable on a vertically disposed shaft 30. It may be observed that the motor 25 is mounted between the pivotal point 20^a for the 85 swinging frame 18 and the sleeve 28 which drives the elevating and rotating mechanism for the cutting mechanism and drives the cutter chain 15^a, that said motor is so placed as to concentrate the center of gravity of the entire cutting mechanism at the pivotal points 20^a and 21^a of the swinging frame 18 and that the distance between the driving end of said motor and the sleeve 28 is such as to enable the use of a relatively large bevel gear for driving 90 said sleeve and obtain a more powerful turning moment than could be obtained if said motor were mounted on the rearward end of said swinging frame. A drive sprocket 31 is keyed on the upper end of said sleeve 100

above said ring in alignment with the cutter arm 15 in position to drive the cutter chain in the usual manner. Said shaft is provided at one end with a head portion 30^a, and the other end with a thrust ring 30^b, so as to maintain the drive in proper alignment. A small bevel gear 32 is mounted on the sleeve 28 adjacent the inside of the larger bevel gear 27 and rotating therewith, and is meshed with a bevel gear 33 which is loosely mounted on a longitudinal drive shaft 34. This shaft is journaled at one end in a bearing 35 formed integral with the main bearing 29, the other end of said shaft extending concentrically through the rear trunnion support, and has a bevel gear 40 keyed on the outer end thereof. Driving engagement between the bevel gear 33 and the shaft 34 is provided through a sliding clutch member 41 feathered on said shaft and movable into and out of engagement with said gear in the usual manner.

The sub-frame 7 carrying the entire cutting mechanism is adjustable vertically through shaft 34 and bevel gear 40 by means of the following mechanism:

The bevel gear 40 is meshed with a pair of oppositely disposed bevel gears 50 and 51, loosely mounted on a transverse shaft 52 extending to the rear of the sub-frame 7, and provided with a reversing clutch mechanism 53 feathered on said shaft in the usual manner to provide reversible driving connections at will.

Two oppositely disposed worm gears 55, 55, are arranged at the rear corners of the sub-frame 7, one at each end of shaft 52, and mesh respectively with worm wheels 55^a, 55^a, mounted on the rear ends of longitudinally extending shafts 56, 56, along opposite sides of said sub-frame 7, to provide a driving connection between shaft 52 and shafts 56, 56. Shafts 56 have pinions 8, 8, keyed thereon which form vertically movable supporting connections with the racks 10, 10, on the upright supports 4, 4, as already described. By means of the reversing clutch 53, it will be seen that the entire cutting mechanism and the sub-frame may be adjusted vertically in either direction under power of the motor 25, so that the cutter arm may be elevated to the desired height to make either a horizontal or shearing cut.

It will be understood that, since the worm gears 55, are adapted to drive in opposite directions at the same time, the shafts 56 will rotate in opposite directions so as to raise or lower both sides of the sub-frame 7 simultaneously. (See Figure 2.) The worm gears 55 are of the self-locking type adapted to maintain the sub-frame 7 at any desired height.

Means are also provided for pivotally swinging the cutter arm 15 and its base plate 16 with respect to the sub-frame and turn-

table in order to feed the cutting mechanism to the coal. As herein shown, this mechanism comprises a gear 60 keyed on the shaft 34 and meshed with a gear 61 disposed on a stub-shaft 62 supported at the rear end of the swinging frame 18. A bevel pinion 63 is integrally connected with the gear 61 so as to rotate therewith and engage a pair of oppositely disposed mitre gears 64, 64, having a reversing clutch mechanism 65^a therebetween on an upright shaft 65. This shaft extends upwardly through and has bearing support in both the upper and lower portions of the swinging frame 18 and has a gear 66 at the upper end thereof, meshed with a gear segment 67 formed integral with and at the rear end of the supporting plate 16. Said gear segment is concentric with the cutter chain sprocket axis about which the cutter arm and its supporting plate 16 may pivot. By means of the mechanism above described, it will be seen that the cutter arm may be driven in an arc in either direction relative to the longitudinal axis of the machine, to be fed to the coal as illustrated in the various positions indicated in Figure 3.

The complete cutting mechanism may be rotated about the horizontal longitudinal axis in the trunnion bearings formed at the front and rear ends of the sub-frame 7, so that the cutter arm may be swung about said axis into various planes ranging from horizontal to vertical, so as to permit horizontal kerfs to be cut above or below said axis or make shearing cuts at either side thereof. In Figure 4 the cutting element is shown in full lines in horizontal position above the trunnion bearings so as to cut a kerf in a horizontal plane, while in dotted lines the cutting element is shown in a vertical position to make a shearing cut with the cutting element at the right side of the axis of said trunnion bearings. Any suitable means that will afford this adjustment may be provided, as for instance, herein a worm gear segment 75 is keyed on to the outer end of the rear trunnion stud 21^a so as to be rotatable with the swinging frame 18 and is meshed with a worm 78 mounted on a transverse operating shaft 77, the outer end of which is provided with an operating wheel 76.

The cutter arm may also be fed to the coal by pivotal movement of the turntable upon which the entire cutting mechanism and motor 25 are supported. As shown herein, the driving means comprises a motor 80 at the rear end of the main frame having driving connection with the turntable through a motor pinion 81, gear 82, shaft 83, worm 84, worm gear 85, shaft 86, gears 87 and 88, shaft 89 and gear 90, the latter named gear being meshed with a toothed periphery 91 of the turntable. The turntable may thus be swung in either direction and in any angle relative to the base frame so as to cut a kerf 130

in any permissible position of the cutter arm either in a vertical or horizontal plane. The machine may also be used for making a slabbing cut along a face parallel with the mine tracks by swinging the turntable so that the cutter arm projects laterally from the main frame and is locked in this position while the machine is propelled along the tracks parallel to the working face, with the cutter arm maintained in a horizontal position.

Suitable means for propelling the truck may be provided as herein shown including a chain 95 driven by a sprocket 96 on one end of shaft 83 and operatively connected thereto through a sliding clutch member 97. Said chain 95 is operatively connected to the outer end of the rear axle through a chain sprocket 98, in the usual manner.

Although I have shown and described one form in which my invention may be embodied, it will be understood that the construction and arrangement of the various parts may be altered without departing from the spirit and scope thereof. Furthermore, I do not wish to be construed as limiting myself to the specific construction illustrated, excepting as it may be specifically limited in the appended claims.

I claim as my invention:

1. In a mining machine mounted on a track guided truck, a main frame, a sub-frame vertically adjustable relative to said main frame, a cutting mechanism rotatable about the longitudinal axis thereof, said cutting mechanism including a swinging frame pivotally supported at both ends in said sub-frame, a motor carried on the forward end of said swinging frame, driving mechanism disposed in said swinging frame engaged by said motor, and a forwardly extending cutter arm operably engaged from said driving mechanism, said cutter arm being pivotally mounted on said swinging frame on an axis perpendicular to said longitudinal axis rearwardly of said motor, and means operated by said driving mechanism for moving said sub-frame and said cutting mechanism vertically between said upright supports.

2. In a mining machine, the combination of a main frame having upright supports thereon, a sub-frame vertically adjustable between said supports, a cutting mechanism rotatable about a longitudinal axis thereof, said cutting mechanism including a swinging frame pivotally supported at front and rear ends on said sub-frame, a motor disposed in the forward end of said swinging frame, driving mechanism disposed rearwardly of and engageable with said motor in said swinging frame, a forwardly extending cutter arm pivotally mounted on said swinging frame and operatively connected with said driving mechanism, and means for moving said sub-frame and cut-

ting mechanism vertically in said supports including power connections from said driving mechanism extending transversely at the rear end of said sub-frame operably engaging drive connections extending longitudinally along each side of said frame and having operable engagement with said upright supports.

3. In a mining machine, the combination of a main frame, a sub-frame vertically movable relative to said main frame, a cutting mechanism pivotally mounted at front and rear ends thereof on a longitudinal axis in said sub-frame, said cutting mechanism including a swinging frame, driving mechanism disposed in the rear end of said swinging frame, a forwardly extending cutter arm pivotally mounted on said swinging frame about an axis perpendicular to said longitudinal axis, and operably engaged by said driving mechanism, a motor disposed in said swinging frame intermediate the forward pivot of said cutting mechanism and the cutter arm pivot axis.

4. In a mining machine mounted on a track guided truck, a turntable, a sub-frame vertically adjustable relative to said turntable, a cutting mechanism rotatable about the longitudinal axis thereof and having pivotal support at both front and rear ends in said sub-frame, said cutting mechanism including a frame, a motor carried at the forward end of said frame, driving mechanism disposed rearwardly of and operably connected to said motor, a cutter arm pivotally mounted on said frame about an axis rearwardly of the axis of rotation of said turntable.

5. In a mining machine, the combination of a main frame, a sub-frame vertically adjustable relative to said main frame, cutting mechanism rotatable about the longitudinal axis thereof, said cutting mechanism including a swinging frame trunnion supported at both front and rear ends in said sub-frame, a motor carried on said swinging frame, driving mechanism disposed in said swinging frame operably connected to said motor, a cutter arm pivotally mounted on said swinging frame and operably engaged from said driving mechanism, means on said cutting mechanism for driving said cutter arm arcuately about an axis perpendicular to said longitudinal axis, means at the rear end and extending longitudinally along the sides of said cutting mechanism adapted to provide said vertical adjustment of said sub-frame relative to said main frame, said driving mechanism including a single power connection from said motor for actuating either of said means.

6. In a mining machine, the combination of a main frame, a turntable thereon, a sub-frame carried on said turntable, a cutting

mechanism rotatable about a longitudinal axis thereof, said cutting mechanism including a swinging frame pivotally supported at front and rear ends on said sub-frame, a motor disposed in the forward end of said swinging frame, driving mechanism disposed rearwardly of and engageable with said motor in said swinging frame, and a forwardly extending cutter arm pivotally mounted on said swinging frame and operatively connected with said driving mechanism.

7. In a mining machine, the combination of a base frame having upright supports thereon, a sub-frame adjustable vertically between said supports, a swinging frame pivotally mounted on a horizontal axis on said sub-frame, a cutter arm mounted for pivotal movement on an axis transverse of the longitudinal axis of said swinging frame, a motor carried by said swinging frame having operative connection with said cutter arm for moving it about its axis, and other power connections concentric with the pivotal connection of said swinging frame and extending therethrough for actuating said elevating adjusting means connecting said sub-frame with the upright supports.

8. In a mining machine, a truck, a turntable mounted on said truck, a sub frame mounted on said turntable and vertically adjustable with respect thereto, a swinging frame supported at its extreme forward and rearward ends on said sub frame for pivotal movement with respect thereto, cutting mechanism supported by said swinging frame and movable therewith including, a motor, a cutter bar extending forwardly from said swinging frame and mounted for pivotal movement with respect thereto about a point rearward of said motor, a cutter chain movable around said cutter bar and driven by said motor, said means for driving said cutter chain being concentric with the pivotal axis of said cutter bar, and a single shaft driven by said motor for vertically adjusting said sub frame with respect to said turntable and moving said cutter arm about its pivotal point.

9. In a mining machine, a truck, a turntable mounted on said truck, a sub frame mounted on said turntable and vertically adjustable with respect thereto, a swinging frame supported at its extreme forward and rearward ends on said sub frame for pivotal movement with respect thereto, cutting mechanism supported by said swinging frame and movable therewith including, a motor, a cutter bar extending forwardly from said swinging frame and mounted for pivotal movement with respect thereto about a point rearward of said motor, a cutter chain movable around said cutter bar and driven by said motor, said means for driving said cutter chain being concentric with the pivotal axis of said cutter bar, a single

shaft driven by said motor for vertically adjusting said sub frame with respect to said turntable and moving said cutter arm about its pivotal point, and means concentric with said shaft but independent therewith for pivotally moving said swinging frame with respect to said sub frame.

10. In a mining machine, a truck, a turntable mounted on said truck, a sub frame mounted on said turntable and vertically adjustable with respect thereto, cutting mechanism rotatable about the longitudinal axis of said sub frame including a swinging frame journaled in said sub frame at both ends thereof and a cutter bar having a cutter chain movable thereabout pivotally mounted on said swinging frame for arcuate movement about an axis perpendicular to the longitudinal axis of said sub frame at a point intermediate the points of pivotal connection of said swinging frame to said sub frame.

11. In a mining machine, a truck, a turntable thereon, a sub frame supported on said turntable for vertical adjustment with respect thereto, cutting mechanism rotatable about the longitudinal axis of said sub frame including a swinging frame journaled in said sub frame at both ends thereof, a motor carried on the forward end of said swinging frame, a cutter arm pivotally mounted on said swinging frame and extending forwardly of said swinging frame, said pivotal axis of said cutter arm being perpendicular to said longitudinal axis of said sub frame and rearwardly of said motor, a cutter chain movable about said cutter arm, cutter chain driving means driven by said motor, said cutter chain driving means being concentric with the pivotal axis of said cutter arm and means rearwardly of the pivotal axis of said cutter arm driven by said motor for moving said cutter arm about its pivotal axis, including a single horizontal shaft on the longitudinal axis of said sub frame said shaft also serving as a driving means for raising and lowering said sub frame with respect to said turntable.

12. In a mining machine, a truck, a turntable mounted on said truck, a sub frame mounted on said turntable and vertically adjustable with respect thereto, cutting mechanism rotatable about the longitudinal axis of said sub frame including a swinging frame journaled in said sub frame at both ends thereof and a cutter bar having a cutter chain movable thereabout pivotally mounted on said swinging frame for arcuate movement about an axis perpendicular to the longitudinal axis of said sub frame at a point intermediate the points of pivotal connection of said swinging frame to said sub frame, and manually operated means concentric with said horizontal longitudinal

shaft but independent therefrom for pivotally moving said cradle with respect to said sub frame.

Signed at Chicago, in the county of Cook and State of Illinois, this 29th day of December, A. D. 1926.
